UNITED STATES PATENT OFFICE.

HARRY F. STRATTON, OF CLEVELAND HEIGHTS, OHIO, ASSIGNOR TO THE ELECTRIC CONTROLLER & MANUFACTURING COMPANY, OF CLEVELAND, OHIO, A CORPORATION OF OHIO.

COMPENSATOR FOR INDUCTION MOTORS.

Application filed July 26, 1922. Serial No. 577,701.

To all whom it may concern:

Be it known that I, HARRY F. STRATTON, a citizen of the United States, residing at Cleveland Heights, in the county of Cuyahoga and State of Ohio, have invented new and useful Improvements in Compensators for Induction Motors, of which the following is a specification.

My invention relates to compensators for induction motors. One of the objects thereof is to provide a device for the class mentioned, in which the starting contacts are closed by a partial operation of a handle, whereby a series transition magnet with its armature initially biased to closed position is energized, there being provision, upon further movement of the handle, for reversing the bias of the armature so that, when the current in the magnet winding is reduced to a predetermined value, a force stored in a spring by the movement of the handle causes the throw of the contacts to running position, together with means for restoring the contacts to off-position directly from running position upon the opening of the motor circuit or the reduction thereof to a predetermined value. This and other objects will be better understood from the description following.

Referring to the accompanying drawings, Fig. 1 is an end view of the mechanical features of my invention, the end of the casing and the handle being removed and Fig. 2, a front view of the said features with the side of the casing removed. Figs. 3, 4 and 5 are somewhat diagrammatic views showing the position of the parts of my invention in their off, starting, and running positions, respectively, and Fig. 6 is a wiring diagram illustrating the operation of the invention.

On the drawings, 1 and 2 represent respectively the front and the rear sides of the casing, and 3 and 4, the right and left ends thereof. 5 is a horizontal shaft or rod supported in the ends 3 and 4 and provided externally of the casing with the handle 6 which is operatively connected to the hub 7 of the lever or arm 8 also carried by the shaft 5.

50 A metal frame 9 having the end members 10 and 11 is pivotally supported on the shaft 5 which passes through the members between their ends. The lower ends of the members support the bar 12 of wood or other insulating material extending parallel with

the shaft 5 and supporting front contacts 13 and rear contacts 14. The upper ends of the members 10 and 11 are connected by the cross-member 15 which has an upwardly offset portion 16 arranged to engage the front end of the stop 17 secured to the rear side 2 of the casing. Within the frame 9 is the frame 18 having the end members 19 and 20 carried by the shaft 5, the horizontal member 21 having the offset portion 22 engageable with the rear stop face 23 on the stop 17. The lower ends of the members 19 and 20 support the bar 24 of insulating material which carries the contact fingers 25 which are engageable with the contacts 13. 60 65 70

To the side 2 of the casing are bolted the two hangers 26 which support at their lower ends the bar 27 of insulating material which carries contacts 28 arranged to be engaged by the contacts 14, only one contact 28 being shown on the bar 27 in Fig. 1. Their inclusion in Fig. 2 would confuse the drawing, but they are shown in Fig. 6.

The arm 8 carries the armature 29 which engages the poles 30 of the magnet 31 secured to the posts 32 on the end 3 of the casing and having the winding or spool 33, 34 being a shading coil on one of the poles 30. The upper end of the arm 8 carries the spring-supported disk or contact 35 which 80 85 bridges the contacts 36 carried by the member 37 of the L-shaped device 38 pivotally supported by the pins 39 extending through the end 3 of the casing and through the member 40 of the device 38, the pins 39 being surrounded by the spring 41 which yieldingly press the member 40 against the inner face of the end 3. The member 40 carries a push-button 42 projecting through the end 3 for operating the device 38 so as 90 95 to move the contacts 36 away from the disk or contact 35 to open the circuit of the winding 33.

A toggle having its members 43 and 44 pivoted together on the pivot 45 has the member 43 carried by the pivot 46 in the portion 16 of the frame 9, and the member 44 carried by the pivot 47 on the lug 48 secured to the front side 1 of the casing. The side 1 supports the bracket 49 on which 100 105 is mounted the magnet 50 having for its armature the upper end of the lever 51 pivoted on the shaft or rod 52 whose ends are supported by the ends 3 and 4. The armature is provided with the spring 53 which 110 115

tends to pull the armature away from the magnet 50.

54 is a lever pivoted between its ends on the pin 55 on the end 3 and having its upper end 68 bent toward the end 4 so as to rest upon the armature 51. A spring 56 stronger than the spring 53 holds the armature against the magnet 50, despite the action of the spring 53 under conditions to be stated 10 presently.

The member 19 of the frame 18 carries a bracket 57 having the top shoulder 58 and the bottom shoulder 59. A coiled spring 60 rests on the shoulder 59 and engages the under side of the finger 61 on the arm 8, the finger 61 engaging the under side of the shoulder 58 when the arm 8 is in its idle position, as shown on Fig. 1. The member 19 carries the bracket 62 and the member 20 10 of the frame 9 carries the bracket 63, connected to the bracket 62 by the loose bolt 64 which limits the spreading apart of the members 10 and 19 below the shaft 5. A coiled spring 65 surrounds the bolt 64 and 25 has its ends engaging the brackets 62 and 63 to hold the frames 9 and 18 in the positions shown on Fig. 1 and to store energy for operating the frame 9 after the spring has been compressed upon the operation of 30 the finger 61, as will be explained presently. The arm 8 has the lug 66 which engages the tail 67 of the lever 54 and rocks the end 68 of the said lever away from the armature 51, thereby leaving the armature under the 35 opening control of the spring 53 and the holding control of the magnet 50. The armature 51 has a lug or cam 69, which operates the toggle members 43 and 44 to flex the same when the armature is actuated by 40 the spring 53, as shown in Fig. 5.

An oil tank 70 is hooked to the lower edge of the casing and surrounds the contacts carried by the bars 12, 24 and 27.

The parts on Figs. 3, 4 and 5 have been 45 somewhat modified in shape and position, in order that parts which lie behind other parts on Figs. 1 and 2, may be readily understood as to their operation.

The parts being initially as in Figs. 1, 2, 50 3 and 6, the handle 6 is moved toward the front, or from right to left, which, before it reaches its final position, causes the finger 61 to act through the spring 60, which is stronger than the spring 65, to compress the 55 latter and move the frame 18 until the contacts 25 engage the contacts 13, after which the portion 22 of the frame 18 engages the stop face 23 and prevents further movement of the frame 18. As soon as the contacts 13 60 and 25 meet, the winding of the transition magnet 50 is energized, as shown in Fig. 6, whereby the magnet attracts the armature 51 with a force stronger than that exerted by the spring 53 to pull the armature away 65 from the magnet. Upon the closing of the

contacts 13 and 25 the supply lines L^1 , L^2 and L^3 are connected to the compensator having the windings 71 and 72, and the motor M is connected to the compensator through taps on the windings 71 and 72 in 70 a manner well known and readily understood from Fig. 6. The motor starts and runs at slow speed.

The handle, when moved still further to its limit, brings the contact 35 into engagement with the contacts 36 whereby a circuit is closed through the no-voltage winding 33 which generates a flux which traverses the poles 30 and the armature 29, and holds the arm 8 in its final position as shown in Figs. 75 4 and 5 until the current in the winding 33 falls to such a value that the flux generated thereby cannot hold the armature 29 against it, or until the push-button 42 is operated to rock the device 38 and move the contacts 36 80 away from the contact 35, thereby opening the circuit of the winding 33, as is clear from Fig. 6.

The said further movement of the handle 90 is permitted by the yielding of the spring 60 under the pressure of the finger 61, and causes the lug 66 by engagement with the finger 67 to rock the biasing lever 54 away from the armature 51, as shown in Fig. 4, thereby leaving the armature under the opposing influences of the spring 53 and the winding 50. As soon as the current in the winding 50 drops to a predetermined value due to the acceleration of the motor, the flux from the winding 50 becomes too weak 95 to hold its armature 51 which then under the influence of the spring 53 moves away from the armature, causing the cam 69 to flex the toggle members 43 and 44, thereby allowing the compressed spring 65 to operate the frame 9 which moves the contacts 13 away from the contacts 25, and the contacts 14 into engagement with the running contacts 28, the contacts 13 and 14 being 100 connected together as shown in Fig. 6. The parts are now as in Fig. 5 and the motor M is connected directly to the supply lines and may run at full speed.

Upon the operation of the push-button 110 42 or the decrease of current in the no-voltage winding 33, the parts move to the positions shown in Figs. 1 and 3 without the starting contacts 25 being again closed, owing to the action of the spring 65 which causes the frames 9 and 18 to return together in spaced relation.

The nut 73 turns on the core 74 of the magnet 50 to adjust the core in the magnet to vary the pull of the latter on the armature 51.

I claim:—

1. In a starting compensator for induction motors, an operating handle, starting contacts engaged upon partial movement of the handle, a magnet energized when the said 130

- contacts are closed, an armature therefor, means for biasing the armature to open position but overcome by the magnet only when the current therein is above a predetermined value, a second means stronger than the first biasing means and opposing the same, means operated on further movement of the handle, for removing the second biasing means after the magnet has been energized, means for storing energy during the operation of the handle, tending to close the running contacts, means for preventing the closing of the running contacts, and means operated by the armature when released from the magnet, for releasing the preventing means, whereby the said stored energy may close the running contacts.
2. In a starting compensator for induction motors, an operating handle, starting contacts engaged upon partial movement of the handle, a magnet energized when the said contacts are closed, an armature therefor, means for biasing the armature to open position but overcome by the magnet only when the current therein is above a predetermined value, a second means stronger than the first biasing means and opposing the same, means operated on further movement of the handle, for removing the second biasing means after the magnet has been energized, means for storing energy during the operation of the handle tending to close the running contacts, means for preventing the closing of the running contacts, means operated by the armature when released from the magnet, for releasing the preventing means, whereby the said stored energy may close the running contacts, and a no-voltage winding for holding the contacts closed.
3. In a starting compensator for induction motors, an operating handle, a motor, starting contacts and running contacts therefor, means actuated by the handle for closing the starting contacts and for storing energy tending to close the running contacts, means restraining the energy-storing means, an electromagnet having its winding energized by the motor current, an armature for the electromagnet biased to open position but prevented from opening when the motor current exceeds a predetermined value, and means controlled by the armature when opening to release the restraining means, whereby the running contacts may close.
4. In a starting compensator for induction motors, an operating handle, a motor, starting contacts and running contacts therefor, means actuated by the handle for closing the starting contacts and for storing energy tending to close the running contacts, means restraining the energy-storing means, an electromagnet having its winding controlled by the motor current, an armature for the electromagnet biased to open position but prevented from opening when the motor current exceeds a predetermined value, and means controlled by the armature when opening to release the restraining means, whereby the running contacts may close.
5. In a starting compensator for induction motors, an operating handle, a motor, starting contacts and running contacts therefor, means actuated by the handle for closing the starting contacts and for storing energy tending to close the running contacts, means restraining the energy-storing means, an electromagnet having its winding controlled by the motor current, an armature for the electromagnet biased to open position but prevented from opening when the motor current exceeds a predetermined value, means controlled by the armature when opening to release the restraining means, whereby the running contacts may close, and a no-voltage electromagnet holding the contacts closed.
6. In a starting compensator for induction motors, an operating handle, a motor, starting contacts and running contacts therefor, means actuated by the handle for closing the starting contacts and for storing energy tending to close the running contacts, means restraining the energy-storing means, an electromagnet having its winding controlled by the motor current, an armature for the electromagnet biased to open position but prevented from opening when the motor current exceeds a predetermined value, means controlled by the armature when opening to release the restraining means, whereby the running contacts may close, and means restraining the opening of the armature until the magnet winding is energized.
7. In a starting compensator for induction motors, an operating handle, a motor, starting contacts and running contacts therefor, means actuated by the handle for closing the starting contacts and for storing energy tending to close the running contacts, means restraining the energy-storing means, an electromagnet having its winding controlled by the motor current, an armature for the electromagnet biased to open position but prevented from opening when the motor current exceeds a predetermined value, means controlled by the armature when opening to release the restraining means, whereby the running contacts may close, and means restraining the opening of the armature until the magnet winding is energized, the latter restraining means being made ineffective upon the operation of the contact-closing means.
8. In a starting compensator for induction motors, an operating handle, a motor, starting contacts and running contacts therefor,

means actuated by the handle for closing the starting contacts and for storing energy tending to close the running contacts, a toggle restraining the energy-storing means, ¹⁰
6 an electromagnet having its winding controlled by the motor current, an armature for the electromagnet biased to open position but prevented from opening when the motor current exceeds a predetermined value, and means controlled by the armature when opening to release the restraining means, whereby the running contacts may close.

Signed at Cleveland, Ohio, this 21st day of July, 1922.

HARRY F. STRATTON.
